UNITED STATES PATENT OFFICE.

HERBERT E. HOLMES, OF WEST SPRINGFIELD, AND CHARLES F. GROSVENOR,
OF LUDLOW, MASSACHUSETTS.

ELECTRIC SAFETY DEVICE FOR ELEVATORS.

SPECIFICATION forming part of Letters Patent No. 443,283, dated December 23, 1890.

Application filed April 14, 1890. Serial No. 347,740. (No model.)

To all whom it may concern:

Be it known that we, HERBERT E. HOLMES and CHARLES F. GROSVENOR, citizens of the United States of America, residing at West 5 Springfield and Ludlow, respectively, in the county of Hampden and State of Massachusetts, have invented new and useful Improvements in Electrical Safety Devices for Elevators, of which the following is a specification.

This invention relates to devices for insuring the automatic stoppage of a moving elevator on the necessity for such stoppage arising from condition of danger, said condition of danger insuring the establishment of an 10 electrical circuit for the control of electrically-operated devices, which in turn have a controlling connection with the power-shipping medium of the elevator, and from the illustrations and description hereinafter given and 15 the terms of the subjoined claims the composition of the invention may be more fully ascertained.

In the drawings, Figure 1 is an illustration in elevation of the usual arrangement of the 20 elevator relative to the hoistway and the power-shipping medium and of the electrically-controlled devices with relation to said power-shipper. Fig. 2 is an enlarged detail view to be hereinafter particularly referred 25 to. Fig. 3 is a view illustrative of certain features of the invention in an application for operation somewhat different from the one shown in Fig. 1.

Corresponding characters of reference indicate the same parts in all the views.

In the drawings, A represents a part of the elevator hoistway, and B a part of the elevator-car, having a usual and well-known form of safety appliances thereon for operating between the car and the vertical ratchet-rack *a* along each side of the hoistway, said safety devices comprising the angular levers *b b*, each having an outwardly-extended dog *d* on the end of its outer arm for projection to engage 40 with said ratchet-teeth, and the spring *f* for insuring the positive and instantaneous movements of the levers on the breakage of the hoist-rope.

C represents the rod, which, however, may 45 be a rope or chain, which connects either directly or through interposed connections with

the belt-shipper or other power-controlling device, and as represented in the particular illustration given the shipper-rod has such a limit of movement as to swing the crank-arm 55 *g* from the position shown into the one indicated by the dotted line 10, the former position, for instance, being that assumed when the elevator is moving downwardly, the latter assumed when the elevator is moving upwardly, and when the shipper-rod is moved to maintain said arm *g* intermediately of said extremity the power will be thrown off and the elevator stopped.

D represents a lever intermediately pivoted 65 on a suitable support and located at some convenient point adjacent the said shipper-rod C, but at such a place in the hoistway that it will not likely be interfered with. This lever normally occupies the oblique position shown in 70 full lines at all times, except on such unusual occasions as the safety devices hereinafter described are required to operate. Said lever is, by its connection with and control by such devices, constrained in said oblique position. 75 The spring *x* is applied to swing the lever from the said normal oblique position to the other oblique position indicated by the dotted lines 12.

h represents a wheel having concentrically 80 affixed on the face thereof another wheel *j*, and said compound wheel is mounted to rotate on the suitably-supported horizontal stud *i*.

The cord or flexible connection *l* is by its 85 terminals connected, as at 14 and 15, to lugs on the shipper-rod C at points above and below the compound wheel *h j*, said cord by an intermediate portion encircling the rim of the wheel *j*, which rim is preferably grooved; and 90 in order that there may be a reliable engagement between the said wheel *j* and the cord encircling it, the cord is at a suitable point—such, for instance, as the part of the periphery farthest from the shipper-rod—confined 95 to the periphery of the said wheel by a staple 16 or other means for positive confinement.

l represents a cord which by one end is connected to the end 17 of lever D and by its 100 other end is connected to the portion, as the lower one 18, of the wheel *h*. *m* represents an-

other cord connected by its one end to the same end 17 of lever D and by its other end to another point, as 19, on the periphery, which latter point is more or less nearly diametrically opposite to the before-mentioned one 18. Both of these cords are of equal length, and in the arrangement stated, when the lever D is in its normal position and the shipper-rod is thrown to its uppermost limit to cause the descent of the elevator, the said shipper-rod will through the cord *l* rotate the compound wheel, so that the point 18 will have a position to make taut the cord *l*, and the cord *m* will be slack. When the shipper-rod C is thrown to its other or lowermost limit, the cord *l*, moving downwardly, insures by its round turn connection with wheel *j* the semi-rotation of the compound wheel *h j*, and the cord *l* is then slackened and the cord *m* is taut, the latter cord then being more or less in the disposition indicated by the dotted line 20. Now it will be seen that whether the shipper-rod is at its upper or lowermost limit to insure either the downward or upward travel of the elevator, one or the other of the cords *l* or *m* between the wheel *h* and lever extremity 17 is taut, and that at either of such times should the lever D under the action of the automatic safety devices connected therewith be swung into the dotted-line position, said lever D will, through whichever cord thereto connected which is taut, insure an extent of rotation of the compound wheel *h j* as will, through the connection of the cord *k* between same and the shipper-rod, secure such a movement of the shipper-rod in its proper direction, either up or down, as the case may be, as to carry the shipper-rod to its midway position—that is, its position for throwing off the power and stopping the elevator; and, again, just as soon as the difficulty occasioned by the slackening of the hoisting-rope has been overcome and the shipper-rod is again thrown to one or the other of its extreme positions it, the shipper-rod, will cause a draft through the cord *k* upon the compound wheel, and the latter through one or the other of the cords *l m*, to effect a restoration of the lever D to its normal position, the same being there maintained by the detent devices comprised in the electrically-controlled contrivances, which will be hereinafter particularly described.

The usual and vertically-movable shaft or spindle *n*, having at its lower end the yoke *b'* for engaging the angular lever *b* at the top of the elevator-car, and to which shaft a hoisting-rope *p* is connected, has a laterally-extended collar *q*, which overlies a spring-contact piece 24, supported on the top of the elevator adjacent to but insulated from another contact-piece 25. An electric wire 26 extends from said contact-piece 24 to an electro-magnet 27, which is in proper proximity to the said lever D, said wire comprising in its run a battery or generator 28. To the other contact-piece 25 another electric wire is con-

nected which passes to an intermediately-pivoted metallic arm 30 adjacent to the electro-magnet, said lever 30 being by its spring 32 normally maintained in the horizontal disposition shown, its one end then resting upon the contact-piece 33, from which contact-piece a short electric wire 29^a also passes to a proper connection with the electro-magnet 27. The armature 35 is comprised in one arm of the angular lever which is pivoted at its elbow, the other arm 36 of said angular lever being adapted to have a latching engagement with the detent device *t* for the disk *u*, with which the lever D has a pin-and-slot engagement, as at 37, said point of engagement being, relative to the normal position of the disk, a little off from a vertical line axially intersecting the disk. The said disk *u* near its lower edge is provided with the laterally-extended stud 38. The said detent device *t* is shown in the enlarged view, Fig. 2, and consists of an L-shaped or elbow lever comprising the members 39 and 40, rigidly united, and the member 42, continuing in a line with the member 39 across and beyond the elbow 43, and a suitable pintle or pivot-pin passes through the elbow and into the supporting plate or part *v*. The spring 44 is applied between the members 39 and 42, which serves in a measure to maintain the relative relations between the three members 39, 40, and 42, shown, although the members 39 and 40 may be swung slightly relatively to the one 42, as indicated by the dotted lines in Fig. 2. The spring 45 is applied to the said detent device *t* for the purpose of swinging the same bodily in the direction indicated by the arrows 46 46 on the unlatching of the armature-arm 36 from its engagement from the member 42. The left-hand arm 47 of the lever 30 overlies a nose 48 of the disk *u*.

The operation of these last-described parts may now be understood. Assuming that in the working of the elevator the hoisting-rope slackens, the shaft *n* is immediately caused to move downwardly in relation to the top of the elevator-car and the collar *q* will bear the contact-piece 24 upon the contact-piece 25, establishing a circuit for the attraction by the electro-magnet of the armature 35 thereupon, and the arm 36 will swing to free the detent *t*. The spring 45 will impart a slight degree of rotational movement to the detent *t* as a whole, so that the extremity of the member 39, which directly acts as the stop for the stud 38, will be swung out of its abutting engagement with said stop. The spring *x* will now swing the lever D and secure a partial rotation of the disk *u* and the movement of the shipper-rod to its intermediate position to secure the shipping of the power. The stop-stud 38, moving into the position indicated therefor by the dotted circle 38^a, Fig. 1, will strike against the member 40 of the detent *t*, which at that time lies across the path of said stud and the detent is forced immediately back to its normal posi-

tion. (Shown in the drawings.) The movement of the disk will swing the lever 30 into the position indicated by the dotted lines therefor, when the circuit will be broken, the 5 end of the said lever 30 passing off from the contact-piece 33, and the armature will fall to its normal position and by its arm 36 latch with the member 42 of the detent. The elevator having been immediately stopped on 10 the slackening of the rope, whereby it is not permitted to assume an oblique disposition and get awry in the hoistway, as otherwise it would be liable to do, the travel of the elevator is then reversed by properly throwing 15 the shipper-rod to the corresponding limit therefor, and the slackening having been thus overcome, as is well known may be readily done, the travel of the elevator in the original direction may be resumed. Under the automatic 20 operation of the electrically-controlled devices above particularly described the disk remains with its stud in the position indicated by 38^a, the lever D being retained in its dotted-line position, and the circuit-breaking lever 25 30 remains in the position indicated therefor by the dotted lines in Fig. 1; but then through the movement secured by the elevator attendant of the shipper-rod to one or the other of its extreme positions, through the 35 compound wheel and cord mechanism *h, j, k*, and *l* or *m*, the lever D is caused to return to its normal position, it in turn carrying the disk *u* to its normal position, the stud 38 thereof as it passes downwardly upon the top 40 of the detent member 39 swinging said detent member, and also the one 40, slightly with relation to the then-latched member 42, so that the said stud 38 may pass by the member 39 and assume its position against the end thereof, the spring 44 then immediately returning the slightly-swung parts of the detent into their proper positions.

From the foregoing description of the mechanism comprised in the present invention it 45 will be seen that the automatically-operating devices are restored to their positions for operation directly the power-shipping medium is so moved as to cause a travel of the elevator in either direction, it obviously appearing that only when the elevator is moving is there any requirement for the protective intervention of the safety devices. It will further appear from the foregoing that under 50 normal conditions the extreme movements of the shipper-rod to insure the travel of the elevator either up or down and the placing of the shipper-rod in its median relation for the stoppage of the elevator in no way affect 55 the operative arrangement of the safety devices.

While in the foregoing description we have 60 made particular mention of the establishment of the circuit to operate devices for insuring the stoppage of the elevator by means of the bearing of the one contact 24 upon the other 65 25, occasioned by the flange or collar *q* moving downwardly on the slackening of the rope, as

occasioned by the slipping of the belt or otherwise, it will be fully apparent that the said devices for controlling the shipper-rod are as 70 advantageously operative on the forming of the circuit through other means—as, for instance, by means of appliances arranged in relation to the elevator-car or hoistway, substantially such as shown and described in an 75 application for Letters Patent of the United States filed by us March 26, 1890, Serial No. 345,313; and in the drawings, Fig. 3, an illustration is given for the purpose of making more clear in what manner the elevator traveling may be immediately stopped by a part 80 of a person or article on the elevator striking against a movable part on one of the floors adjacent the hoistway. As the said movable part E is upwardly forced by being 85 borne upon by a projecting part or person on the elevator, the pin 50 is therewith moved to release the contact-piece 24^a, so that it may bear upon the contact-piece 25^a, it being noted that the electrical wires 26 and 29 connect 90 with these contact-pieces, and thus it will be seen that it is quite immaterial in what particular manner the circuit is established, for the operation of the parts directly controlled by the electro-magnet is in no way dependent upon circuit-closing devices having any 95 particular manner of operation.

What we claim as our invention is—

1. In a safety device for elevators, the combination, with the power-shipping medium, as 100 the shipper-rod C, of a lever D, pivotally supported, and a wheel axially mounted for partial rotation, a cord having connections at different points thereof with said power-shipping medium and also with said wheel, and 105 cords connected to different peripheral portions of said wheel and to said lever, and all whereby on the swinging of said lever said wheel will be rotated and the shipper-rod will be moved to its intermediate or power-shifting 110 position, substantially as described.

2. In a safety device for elevators, the combination, with the power-shipper, of a lever D, pivotally supported, and a wheel axially mounted for partial rotation, the cord having 115 connections at different points thereof with said power-shipping medium and also with said wheel, and cords connected to different peripheral portions of said wheel and to said lever, as and for the purpose set forth, 120 an electro-magnet and mechanism controlled thereby for restraining or controlling the swinging of said lever, contact-pieces properly applied in relation to the elevator, the one adapted to be moved against the other, 125 and electric connections running from said contact-pieces to the said electro-magnet and comprising an electric generator, for the purpose described.

3. In a power-shipping mechanism for elevators, in combination, the power-shifter rod, a swinging lever, and connections interposed between same and said power-shipper for insuring on the movement of said lever the 130

placing of said power-shipper into its position for insuring the non-operation of the motive power, a disk with which said lever has an engagement, substantially as described, and provided with an abutment part, as 38, a detent for engagement with said abutment, and a spring 45, applied thereto for bodily swinging said detent, the electro-magnet, and the armature comprising by a suitable part thereof a latch for said detent, and the contact-pieces properly applied in relation to the elevator, the one adapted to be moved against the other, and electric connections running from said contact-pieces to the said electro-magnet and comprising an electric generator, for the purpose described.

4. In a safety device for elevators, the combination, with the elevator-car having the insulated and separated contact-pieces 24 and 25, the one adapted to be moved to contact with the other, and the part *q*, movable on the slackening of the hoist-rope to insure the contacting of said pieces, and the power-shipping medium, of an electro-magnet and wires running therefrom to said contact-pieces and comprising the electric generator, and movable connections actuated by said electro-magnet and interposed between same and said power-shipping medium, whereby on the closing of the circuit the said movable connections will insure the shifting movement of the said shipper.

5. In a safety device for elevators, the combination, with a power-shipping medium, of a swinging and spring-constrained lever, as *D*, and interposed connections between same

and said power-shipping medium for insuring on its movement the placing of said medium into its shifting position, a disk with which said lever has an engagement, substantially as described, and provided with the abutment-stud 38 and the nose 48, and capable of a partial rotation, the pivotally-mounted detent *t*, comprising the rigid members 39 and 40 and the member 42, and the spring 45 applied between the latter member and one of its fellows, for the purpose set forth, and the spring 45 for bodily swinging said detent, the spring-pressed circuit-breaking lever 30, having an arm in engagement with said nose 48, and a contact-piece 33, on which said lever normally bears, the electro-magnet and its armature, which has a latching engagement with said detent, contact-pieces properly applied in relation to the elevator, the one adapted to be moved against the other, an electric connection running from one of said contact-pieces to said latter-named electro-magnet, an electric connection running from the other of said latter-named contact-pieces to said circuit-breaking lever 30, and another connection between said first-named contact-piece 33 and the electro-magnet, there being comprised in the circuit an electric generator, all arranged for operation substantially as and for the purpose described.
